UNITED STATES PATENT OFFICE.

THEOPHILE EDOUARD AYOTTE AND ARTHUR ALBERT CHARBONNEAU, OF MONTREAL, CANADA.

APPARATUS FOR LOADING OR UNLOADING BRICKS.

SPECIFICATION forming part of Letters Patent No. 664,711, dated December 25, 1900.

Original application filed October 9, 1897, Serial No. 654,662. Divided and this application filed July 7, 1899. Serial No. 723,045. (No model.)

To all whom it may concern:

Be it known that we, THEOPHILE EDOUARD AYOTTE and ARTHUR ALBERT CHARBONNEAU, subjects of Her Majesty the Queen of Great Britain, residing at the city and district of Montreal, Province of Quebec, Canada, have invented certain new and useful Improvements in Apparatus for Loading or Unloading Bricks; and we do hereby declare that the following is a full, clear, and exact description of the invention, such as will enable others skilled in the art to which it appertains to make and use the same.

This invention relates to apparatus for loading and unloading brick; and its object is to provide an apparatus of this character by means of which brick may be readily and safely transferred into cars or deposited in a pile.

To this end the invention consists in an apparatus for loading and unloading brick, constructed substantially as hereinafter illustrated, and described and defined in the appended claims.

Referring to the drawings, in which similar numerals of reference indicate similar parts throughout the several views, Figure 1 is a side elevation of an elevator and car employed for carrying finished brick or other material from the press. Fig. 2 is an end view thereof with the car and the elevator and conveyer being omitted. Fig. 3 is a perspective detail view of the elevator and conveyer for transferring the brick to the car. Fig. 4 is a detail view.

The apparatus herein described and illustrated is especially adapted for use in connection with a brick-machine, for which United States Letters Patent No. 625,866 were granted to us, dated May 30, 1899, though it is evident that its use is not restricted to such machine, but is adapted generally for use wherever needed.

In the drawings, 67 represents the frame of an elevating apparatus, which is suitably braced to give it the requisite strength. Mounted in the lower portion of the frame 67 is a shaft 68, to which rotary motion may be imparted by any desired means. Movable

longitudinally of the shaft, but adapted to 50 rotate therewith, is a sleeve 69, having a clutch-section at each end, one of said sections being adapted for engagement with a clutch-section 70, loosely mounted on the shaft 68 and with which a sprocket-wheel 71 55 is connected. From the sprocket-wheel 71 a sprocket-chain 72 extends to a sprocket-wheel 73 on a shaft 74. The opposite end of the sleeve 69 is provided with a clutch-section 60 adapted to be engaged with a clutch-section 76 on the miter-pinion 75, loosely mounted on the shaft 68, and meshing with a bevel-pinion 76 on the lower end of a shaft 77, extending vertically and having bearings in the frame 67. Near each end of the shaft 74 is mounted 65 a drum 78, from which cables 79 and 80 extend around pulleys 81 and 82, and thence over pulleys 83 and 84 at the top of the frame 67, and from these pulleys 83 and 84 the cables extend downward and connect with an 70 elevator made in the form of an endless carrier 85, mounted to rotate around a frame 86, from the corners of which pins extend into channels formed in the corner-posts of the frame 67, said pins forming the guides for 75 said frame 86. The carrier 85 (best shown in Fig. 3) is movable around rollers 85^a on shafts having bearings in the frame 86, and on the shaft of one set of rollers is a bevel-gear 87, meshing with a bevel-gear 88, mounted to move longitudinally of the shaft 77, but to rotate therewith. As here shown, the shaft 77 is provided with a longitudinal slot 80 to receive a feather carried by the pinion 88, although it is clear that the relative arrangement of the slot and feather may be reversed, if desired.

Mounted to rotate at one side of the frame 67 is a shaft 89, which is also mounted to move vertically of said frame by reason of 90 its connection with the rod 100, which connection may be made in any suitable manner, one form being shown in Fig. 4, wherein the rod 100 is shown as formed with an enlarged head which rests within a recess formed in 95 the shaft 89, a suitable plug or washer serving to retain the head in position. Spirally disposed on this shaft 89 is a series of out-

wardly-extended pins 90, the spaces between which are equal to the spaces between floors 91 of a transporting-car 92, and on the lower end of the shaft 89 is a pinion 93, having a 5 number of teeth equal to the number of pins 90. Adapted to engage with this pinion 93 is a dog 94, carried by a longitudinally-moving bar 95, at one end of which is an inwardly-extended arm 96, (see Fig. 2,) adapted to be 10 engaged with a carrier-rack 66, as hereinafter described. From the opposite end of the bar 95 a lever 97 extends and is pivoted near its lower end to the base of the frame 67, and from this lower end a link 98 extends to a 15 pivotal connection with a lever 99. From the other end of this lever 99 a rod 100 extends upwardly to the shaft 89, with which it is connected in any suitable manner.

In operation it will be assumed that a rack 20 66, having a load of brick thereon, is to be placed in the first or lowest compartment of the car 92. As the said rack is moved onto the elevator 85 by any suitable means, such as chains leading from a brick-molding machine, such as is described in Patent No. 625,866, filed October 9, 1897, Serial No. 654,662, of which this is a divisional application, and as said rack approaches the end of its movement it will engage against the arm 25 96 and move the bar 95 longitudinally. This longitudinal movement of the bar 95 will cause its dog 94 to move the pinion 93 one 30 step, and thus impart a partial rotary movement of the shaft 89 and move the first pin 35 90 on said shaft 89 into the line of upward movement of the elevator. At this time the clutch-section 69 will be moved into engagement with the clutch-section 70 by means of the lever 97, which extends into an annular 40 channel formed in the clutch-section 69. When the clutch-sections 69 and 70 are thus engaged, the shaft 74 will be rotated to raise the elevator 85. When the elevator shall have been raised sufficiently high to engage 45 the rack 66 with the pin 90, the shaft 89 will be moved upward, disengaging the pinion 93 from the dog 94, and by pulling up the rod 100 will rock the lever 97 to move the clutch-section 69 into engagement with the clutch- 50 section on pinion 75, thus releasing the section 70 from operative connection with the shaft 68, said section and the parts controlled by its movement being held stationary by any suitable means—such, for instance, as 55 the counterbalanced lever 71^a. The movement of the section 69 into engagement with the miter 76 causes a movement to be imparted to the shaft 77, and consequently move the endless carrier 85 to force the rack 60 66 into the compartment of the car. The lever 71^a normally contacts with the periphery of the head of the wheel 71, but is adapted to be freed from such contact by hand or otherwise, as may be necessary in allowing 65 the carrier to have its vertical movement. As the bar 95 and its connections control and are controlled by the movement of the clutch-

section 69, it will be readily seen that while the said bar is moved in one direction by the movement of the carrier striking the portion 70 96 thereof, thus moving the clutch-section, said bar is returned to its normal position by the reverse movement of the clutch-section, caused by the changing of the position of the rod 97, as hereinbefore set forth. This 75 operation will continue until all the compartments are filled.

While we have herein shown a preferred form of carrying our invention into effect, yet we do not desire to limit ourselves to such 80 preferred details of construction, but claim the right to use any and all modifications thereof which will serve to carry into effect the objects to be attained by this invention in so far as such modifications and changes may 85 fall within the spirit and scope of our said invention.

We claim—

1. An elevating conveyer comprising a frame; a receiver movable vertically therein, 90 said receiver being adapted to receive the material; a rotary shaft carried by said frame; means for intermittently connecting said shaft operatively with said receiver, whereby the latter will be intermittently raised; and 95 means for automatically regulating the distance of movement of said receiver, the stopping-point of said receiver varying with each raising movement.

2. An elevating conveyer comprising a 100 frame; a horizontally-traveling receiver movable vertically therein, said receiver being adapted to receive the material; a rotary shaft carried by said frame; means for intermittently connecting said shaft operatively with 105 said receiver, whereby the latter will be intermittently raised; and means for automatically regulating the distance of movement of said receiver, the stopping-point of said receiver varying with each raising movement. 110

3. An elevating conveyer comprising a frame; a horizontally-traveling receiver movable vertically therein; said receiver being adapted to receive the material; a rotary shaft carried by said frame; automatic means for 115 intermittently connecting said shaft operatively with said receiver, whereby the latter will be intermittently raised; and means for automatically regulating the distance of movement of said receiver, the stopping-point of said receiver varying with each raising movement. 120

4. An elevating conveyer comprising a frame; a horizontally-traveling receiver movable vertically therein, said receiver being 125 adapted to receive the material; a rotary shaft carried by said frame; means for intermittently connecting said shaft operatively with said receiver, whereby the latter will be intermittently raised; means for automatically regulating the distance of movement of said receiver, the stopping-point of said receiver varying with each raising movement, and a carrier adapted to receive the material 130

from said receiver, said carrier having provision to receive the material at the different raised positions of said receiver.

5. An elevating conveyer comprising a frame; a horizontally-traveling receiver movable vertically therein, said receiver being adapted to receive the material; a rotary shaft carried by said frame; means for intermittently connecting said shaft operatively with said receiver, whereby the latter will be intermittently raised; means for automatically regulating the distance of movement of said receiver, the stopping-point of said receiver varying with each raising movement; a carrier adapted to receive the material from said receiver, said carrier being removably held in juxtaposition to said receiver, the latter automatically delivering the material to said carrier; and means for releasing said carrier.

6. An elevator, comprising a frame; a rotary shaft in said frame; a horizontally-disposed frame; cables extended from said horizontally-disposed frame over pulleys on the first-named frame, the said cables being operated from the rotary shaft to raise and lower the horizontally-disposed frame; an endless carrier movable around the frame; and means operated by the shaft for moving said endless carrier to discharge its load of material, substantially as specified.

7. An elevator, comprising a frame; an elevator - platform movable vertically in said frame; an endless carrier movable around said platform; means for causing these move-

ments; a rotary shaft having a spirally-disposed row of pins forming stops for the elevator; and a car divided into compartments for receiving material from the elevator, substantially as specified.

8. An elevator for receiving brick from the carrying devices, the said elevator comprising a frame; a horizontally-disposed frame movable vertically in the first-named frame; an endless carrier movable around the horizontally-disposed frame; rollers carried by said horizontally-disposed frame and upon which the carrier moves; a gear-wheel on the shaft of a pair of said wheels; a vertically-disposed shaft on the first-named frame; a gear-wheel movable vertically on and mounted to rotate with said shaft, said gear-wheel engaging with the first-named gear-wheel; a main shaft for operating the vertical shaft; a shaft mounted in the first-named frame so as to rotate and move vertically therein; a spirally-disposed row of pins on said shaft; a pinion on the lower end of said shaft; a dog extended from a rod for imparting a step-by-step motion to said shaft having the pins; and a clutch mechanism on the main shaft operated from said rod, substantially as specified.

In witness whereof we have hereunto set our hands in the presence of two witnesses.
